JULES J. LINTZ,
Inventor,

By his attorney, W. J. Abbott

UNITED STATES PATENT OFFICE.

JULES J. LINTZ, OF MONTCLAIR, NEW JERSEY.

PHOTOGRAPHIC PLATE AND FILM LIFTER.

No. 808,936.

Specification of Letters Patent.

Patented Jan. 2, 1906.

Application filed September 29, 1904. Serial No. 226,439.

To all whom it may concern:

Be it known that I, JULES J. LINTZ, a citizen of the Republic of France, and a resident of Montclair, in the county of Essex and 5 State of New Jersey, have invented certain new and useful Improvements in Photographic Plate and Film Lifters, of which the following is a specification.

The object of my invention is to provide a 10 lifter which while simple in construction shall at the same time be capable of use not only with varying sizes of plates, but also with films, and shall so hold the plate or film that access to its surface to touch it up with 15 a brush may be permitted when required.

Referring to the accompanying drawings, which form a part of this specification, Figure 1 is an isometric projection showing the upper surface of the lifter with a plate and 20 film clamped therein; Fig. 2, a transverse section taken in the plane $x-x$ of Fig. 1 with the plate, the film, and the handle broken away. Fig. 3, a plan view showing a lifter of a 25 slightly-modified form and a plate clamped therein; Fig. 4, a transverse section taken in the plane $y-y$ of Fig. 3 with the plate and handle broken away; and Fig. 5, a plan view of the construction shown in Fig. 3, but showing the clamping of the plate effected with 30 the parts in a slightly different relationship.

In all the figures like letters of reference indicate corresponding parts.

A indicates jaws which engage with the edges of the plate or the film, and B indicates 35 a handle by means of which the manipulation or handling of the plate or film is effected. The jaws A may be constructed of any appropriate material that will not be affected by either the developing or fixing solutions. 40 I prefer, however, to construct them of hard rubber and to provide them on their inner edges with grooves a for receiving the edges of the plate or film that is to be treated. In some cases these jaws will be constructed of a 45 length approximating that of the plate or film in connection with which they are to be employed, and when thus constructed the grooves a in their edges will preferably be formed of the contour in cross-section of that 50 shown in Fig. 2, whereby to permit of holding not only the edges of plate C when a plate is employed alone, but the edge of a film D and its supporting-plate E when a film is made use of, as shown in Fig. 1. In other cases, on the 55 other hand, these jaws A instead of extending throughout the greater portion of the length

of the plate or film will be very much shortened, as shown, for instance, in Fig. 3, and when this form is employed the lifter will be used in connection with plates alone, and the 60 grooves a , formed in their inner faces, will preferably be of a V-shaped construction in cross-section, as shown in Fig. 4. With this last-mentioned construction these jaws in operation will either engage with the opposite edges of the plate C, near one end thereof, as shown in Fig. 3, or be so disposed that one jaw will engage with one edge near one of its ends and the other jaw engage with its other edge near the opposite end thereof, as 70 shown in Fig. 5, and when thus disposed in this last-mentioned relationship they may be employed in connection with a supporting-plate, as F, to sustain a film when placed thereon. 75

While the jaws A are constructed as thus explained, the handle B may be of various forms. I prefer, however, to construct it of flexible material—as, for instance, of wire—which may be made from German silver or 80 other suitable material that will be unaffected by the developing or fixing solutions, and to form its outer end in the shape of a loop b , with two arms or members b' extending inward from this loop and disposed the one 85 across the other, with the inner end of each bent downward at an angle to its body portion and forming at its extremity a pivot upon which one of the jaws A is rotatively mounted, whereby to be capable of rotation 90 around the same. The manner of mounting the jaws A upon these extremities may be modified in various ways. I prefer, however, to accomplish that result by reducing the diameter of the inner extremities of the 95 arms or members whereby to form shoulders b^2 and to arrange these reduced portions b^3 in suitable orifices formed in the respective jaws, in which relationship they may be secured by upsetting or riveting down their 100 extreme ends, with metal washers b^4 interposed between the jaws and the respective shoulders b^2 and the upset or riveted extremities, as shown. By this means of securement the requisite friction to hold the jaws in proper 105 relationship to the handle when seizing a plate may be insured, which may be increased when it becomes more or less diminished by use by further upsetting or riveting down the end of the reduced portions b^3 , as will be readily understood. 110

As thus constructed the separation of the

jaws to engage any particular size plate or film may be effected by simply pressing together the loop-shaped handle B with the hand, the result of which will be to cause the 5 jaws to move outward into the position shown by dotted lines in Figs. 1 and 3, and in order to insure of this outward movement being more effectually accomplished while holding the two arms or members of the handle in 10 close relationship at the point of their crossing I surround them at that point with a ring E, which loosely embraces them. The jaws A having been thus separated to receive the plate, their engagement with the edges of the 15 latter will be effected by releasing the gripping action of the hand upon the loop b, when these jaws will by the resiliency possessed by the loop approach and engage with the edges thereof, and the plate when used alone is 20 then ready for immersion into the required solution or other manipulation, as may be desired. On the other hand, when the lifter is used in connection with a film D a supporting-plate F is employed, which is first grasped 25 between the jaws A and the film D, then placed and supported upon it, as shown in Fig. 1. The film D being thus supported may then be immersed in the different solutions and subjected to such other treatment 30 as may be required, and in order to permit of its removal from the lifter when desirable or necessary without disturbing the supporting-plate F this supporting-plate is preferably provided at one end or both with a recess or 35 recesses e to allow of the fingers passing through it or them to engage with the film.

With the parts constructed and arranged as above explained a lifter is provided which is not only simple in construction and convenient in operation, but in consequence of the wide limits of movement allowed to its holding-jaws toward and away from each other is adapted to coöperate with plates or films of various widths and sizes and not only 40 supports and firmly holds them during the various operations through which they are passed, but permits of their being touched up with a brush when required without interfering therewith.

50 While in the drawings I have shown and in the above have described the invention as employed only in connection with plates and films, it is to be understood that the inven-

tion is adapted to be used in connection with "paper negatives" and "developing positive 55 paper," and in practice I contemplate so using it.

Having now described my invention and specified certain of the ways in which it is or may be carried into effect, I claim and desire 60 to secure by Letters Patent of the United States—

1. The combination, with a pair of holding-jaws provided with a longitudinally-disposed groove in the inner edge of each, of a 65 handle composed of two arms or members with the inner end of each bent at an angle to the plane of the said handle and having one of such holding-jaws pivoted directly on each of these inner bent ends, whereby to be 70 capable of a rotary movement around the same, substantially as described.

2. The combination, with a handle constructed of resilient material and having a loop in its outer end with two arms or members disposed across each other, and the inner end portion of each bent at an angle to the plane of the said handle, of a holding-jaw pivoted directly upon the inner bent end of each of these arms or members, whereby 75 to be capable of rotation around the same, and provided with a longitudinally-disposed groove in its inner edge, substantially as described.

3. The combination, with a handle constructed of resilient material and having a loop in its outer end with two arms or members crossing each other and bent at their inner ends at an angle to their respective body portions, and a holding-jaw pivoted directly 85 upon the inner bent end of each of these arms or members whereby to be rotatable around the same, and provided with a longitudinally-disposed groove in its inner edge, of a supporting-plate adapted to be gripped and supported between such jaws and provided with 90 means at its end or ends through which the finger of the operator may pass to seize the end of a film or paper supported upon such plate, substantially as described.

In witness whereof I have hereunto set my hand this 27th day of September, 1904.

JULES J. LINTZ.
